OIL BURNER

Filed May 27, 1930

Fig. 1.

Fig. 2.

UNITED STATES PATENT OFFICE

WILLIAM C. MCKESSON, OF CHICAGO, ILLINOIS

OIL BURNER

Application filed May 27, 1930. Serial No. 456,246.

This invention relates to certain novel improvements in oil burners, and has for its principal object the provision of an improved construction of this character which will be highly efficient in use and economical in manufacture.

It is well known in the art relating to oil burners that the heating efficiency and operation of the burner is greatly affected by the presence of carbon or other like foreign matter which results from the burned oil. Allowing any deposits of carbon upon the burner or any other element of the oil burner which is within heating range of the flame, will tend to lower the efficiency of the apparatus. It is, therefore, one of the many objects of this invention to provide an oil burner with a simple arrangement of parts for effecting the removal of carbon deposits or the like.

A still further object of this invention is to provide an oil burner which adapted to be used in connection with a gravity fuel feed arrangement. To accomplish this and to obtain the best results it is advantageous that the oil be vaporized prior to its introduction to the flame. It is, therefore, one of the objects of this invention to provide an oil burner which will accomplish this purpose.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a side view of a heating apparatus with parts thereof removed illustrating my invention associated with the interior of the heating apparatus;

Fig. 2 is a sectional detail view of the oil burner embodying my invention;

Fig. 3 is a perspective view of a distributor head embodied in the invention;

Fig. 4 is a top plan view of the same;

Fig. 5 is a part sectional detail view taken substantially on line 5—5 of Fig. 4; and

Fig. 6 is a sectional detail view taken substantially on line 6—6 of Fig. 5.

Referring particularly to Fig. 1 illustrating a conventional heating apparatus with which my oil burner may be associated, this apparatus includes a body 10 defining a combustion chamber 11 and a pit 12, the pit 12 being separated from the combustion chamber by the usual grates 13. Communicating with the pit 12 is a draft and clean-out door 14.

With an apparatus of this character or of similar character my improved oil burner is adapted to be associated.

My improved oil burner in the present instance preferably includes a pipe member 15 having its lower end portion provided with screw threads 16. Threaded upon this pipe 15 is a pan or dish element 17 which includes an upstanding annular flange 18. Above the pan or dish-like element 17 is a distributor head 19. This distributor head 19 in the present instance includes a nipple 20 threaded upon the pipe 16, and threaded upon this nipple is a cup 21. This cup 21 includes at spaced intervals upstanding lugs or fingers 22, and the inner edges 23 of these fingers 22 terminate into tapered projections 24 for reasons hereinafter set forth.

The cup 21 is preferably filled with a suitable fire clay 25 or the like or other refractory substance for heat intensifying purposes. Surrounding the upper end portion of the pipe 15 is an outer pipe 26. This outer pipe 26 is of a diameter sufficient to afford positioning of the pipe 26 between the lugs or fingers 22, and the lower edge of the pipe 26 is beveled upwardly and inwardly as at 27, this lower edge 27 being adapted to seat upon the projections 24.

Threaded upon the end portion of the pipe 26 is a body 28 having a hollow interior 29 to provide a vaporizing chamber. This body 28 is threaded as at 30 to the pipe 26. As shown, the upper end portion of the pipe 15 extends through the pipe 26 with its end into the chamber 29, and threaded upon this end is a baffle head 31. This baffle head 31 includes oppositely disposed parallel grooves 32 which merge at their corners into outlet grooves 33.

The end 34 of the pipe 26 is preferably 100

tapered upwardly and inwardly to provide knife shaped edges which engage in the ports or notches 49 as shown, for reasons herein-after set forth.

The body 28 is provided with a central opening 35, and threaded in this opening is a nipple 36. Threaded into this nipple 36 is a plug 37. This plug has threaded therein a set screw 38, and formed preferably as an integral part of this set screw is a depending scraper bar 39 which extends downwardly substantially through the pipe 15 to a point adjacent its lower end portion. Fixed to the pipe 15 adjacent the pipe 26 there is also a scraper bar 40. This scraper bar 40 has its upper end portion 41 positioned into a slot 42 formed in the baffle head 31. The lower end portion of this scraper bar is angled and projected through an opening 43 formed in the pipe 15 and secured therein in any suitable manner, such for example, as by means of a rivet head 44.

When in use it has been my experience that the body 28 providing the vaporizing chamber becomes intensely hot and has a tendency to crack transversely. To avoid this I provide on the under surface 45 of the body 28 concentrically arranged ribs 46 which will resist the cracking of the body 28 by reason of the intensity of the heat.

Associated with the pan or dish like member 17 is an overflow pipe 47 which is directed to deliver excessive oil fuel to a bucket or other basin (not shown) controlling a suitable valve structure such as described in my co-pending application Ser. No. 456,245 filed by me on even date in the United States Patent Office. Also associated with this basin or dish like member is an air delivery pipe 48 which has its end portion confined in the draft pit 12 of the stove.

In use, the several parts are assembled in the manner illustrated in Fig. 2 with the basin or dish like member 17 threaded up against the nipple 20 which has the effect of a lock nut locking the several parts in their respective positions. The oil burner is then arranged in the heating apparatus by projecting the pipes 47 and 48 through the grates with the basin or dish like member supported upon the grate. If the grate be of a duplex type the mounting of the burner in the heating apparatus may be greatly facilitated by opening the grates to permit the pipes 47 and 48 to be projected therethrough. However, if the grates are not of this type suitable openings may be formed in the grates for the projection of these pipes.

Oil or other suitable fuel is admitted into the pipe 15. By gravity it is forced upwardly through this pipe into the vaporizing chamber 29. The oil finds its entrance into this chamber through the outlet grooves 33. It will be noted that the end 34 of the pipe 26 projects a predetermined distance into this

chamber so that consequently a certain amount of oil will find lodgement in this chamber. From the chamber the oil passes after it reaches a certain level, through the notches or ports 49 formed in the underside 70 of the baffle head 21, into the pipe 26 and downwardly through the pipe 26 into the distributing cup 19 and from whence into the basin or dish like member 17. Any excessive amount of oil at this stage of operation will be drained through the pipe 47. At this stage of the operation the valve controlling the supply of oil through the pipe 15 is closed. The oil in the basin or dish like 75 pan 17 is ignited. This can be accomplished by suitable light or by means of an inflammable piece of material such as paper or the like which is ignited and projected into the basin or dish like member 17. The heat thus generated will heat the vaporizing chamber 80 and consequently the oil therein will become vaporized and move through notches 49 and downwardly through the pipe 26 into contact with the flame of the oil in the member 17 and thereby become ignited. The valve 85 is now opened to admit the oil through the pipe 15 and as the oil enters the chamber 29 it becomes vaporized and emerges from the pipe 26 in a vaporized condition to be ignited and burned.

It is a known fact that all oil will dispose carbon on the heated parts and as indicated it is one of the many objects of this invention to provide a simple means for removing this carbon without disassembling the burner.

Any carbon disposed on the pipe 15 is removed by the carbon removing bar 39. This is accomplished by rotating the vaporizing chamber 28, which in turn will rotate the bar 39, rubbing the longitudinal edges thereof against the interior surface of the pipe 15. Carbon is removed from the end 34 which constitutes a seat for the baffle head 31 and this is likewise accomplished by rotating the vaporizing chamber which will cause the 100 notched portions 49 of the baffle head to rub over the knife like edges of the end 34 and thereby to cut the carbon from the baffle seat. Carbon is likewise removed from the lower end portion of the pipe 26 upon rotation of 105 the vaporizing chamber 29. Upon rotation of this chamber 29 the pipe 26 will be rotated therewith and the projections 24 will scrape the beveled edge 27 of the pipe 26 and consequently remove the carbon deposits 110 therefrom.

As shown the body 28 is provided with a plurality of radially extending fins 28' for conductive purposes and in rotating this body and its several parts for removing the carbon 115 the user may apply the end of a poker or other instrument to these ends to facilitate this rotation.

Any carbon deposits within the pipe 26 are removed by the bar 41 which is accom-

plished by rotating the pipe 26 through rotation of the body 28.

From the description herein it will be seen that the user of an oil burner such as herein described can readily remove the carbon deposits which diminish the efficiency of the burner by simply rotating the oil burner in the manner herein described.

The present invention constitutes an improvement over that disclosed in my United States patent granted December 31, 1929, Patent No. 1,741,868.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In an oil burner, a body providing a vaporizing chamber, a supply conduit, a baffle head on said conduit within said chamber, a second conduit surrounding said first mentioned conduit and having an end portion projecting into said chamber and provided with a beveled edge adapted to engage in a groove formed in the baffle head, a clean-out member supported by the body and extending into said first mentioned conduit, a pan supported by said first mentioned conduit, and a distributor head between said pan and the lower end portion of said second mentioned conduit.

2. In an oil burner, a body providing a vaporizing chamber, a supply conduit, a baffle head on said conduit within said chamber, a second conduit surrounding said first mentioned conduit and having an end portion projecting into said chamber and provided with a beveled edge adapted to engage in a groove formed in the baffle head, a clean-out member supported by the body and extending into said first mentioned conduit, a pan supported by said first mentioned conduit, and a distributor head between said pan and the lower end portion of said second mentioned conduit, said distributor head including beveled projections providing seats for the lower end portion of said second mentioned conduit and said seats being adapted for scraping engagement with said lower end portion of said second mentioned conduit upon rotation of said conduit and said body.

3. An oil burner including a body providing a vaporizing chamber, a pan below said chamber, means providing connection between said pan and said chamber, said means including a conduit having a lower edge portion provided with a beveled edge, and a dis-

tributor cap including beveled projections adapted to engage the beveled edge of said conduit.

4. An oil burner including a body providing a vaporizing chamber, a pan below said chamber, means providing connection between said pan and said chamber, said means including a conduit having a lower edge portion provided with a beveled edge, and a distributor cap including beveled projections adapted to engage the beveled edge of said conduit, said distributor cap providing spaced lug members between which said conduit is adapted to be positioned.

5. An oil burner including a body providing a vaporizing chamber, an oil pan disposed beneath the vaporizing chamber, means providing communicable connection between said vaporizing chamber and said oil pan, said means including a supply conduit, a baffle head carried by the conduit, a second conduit having one end portion projecting into the chamber and provided with a beveled edge for rubbing engagement in grooves formed in the baffle head, and a scraper bar supported by the vaporizing body and extending into said first mentioned conduit.

6. In combination with an oil pan having an air supply conduit leading thereto, an oil burner including a body providing a vaporizing chamber above the oil pan, means providing communicable connection between said vaporizing chamber and said oil pan, said means including a supply conduit, a baffle head carried by the conduit, a second conduit having one end portion projecting into the chamber and provided with a beveled edge for rubbing engagement in grooves formed in the baffle head, and a scraper bar supported by the vaporizing body and extending into said first mentioned conduit.

In testimony whereof I affix my signature.

WILLIAM C. MCKESSON.
